UNITED STATES PATENT OFFICE.

FRANKLIN WILLIAM KREMER, OF CARLSTADT, NEW JERSEY.

CORE-CHUCK.

1,008,652.

Specification of Letters Patent. Patented Nov. 14, 1911.

Application filed February 8, 1911. Serial No. 607,275.

To all whom it may concern:

Be it known that I, FRANKLIN W. KREMER, a citizen of the United States, residing at Carlstadt, in the county of Bergen and State of New Jersey, have invented a new and useful Core-Chuck, of which the following is a specification.

The device forming the subject matter of this patent, is a chuck, adapted for holding and securing the cores or building forms used in the construction of vehicle tires. Chucks of this character, as at present constructed, embrace a plurality of radially moving supporting elements, adapted to engage the core, each of these supporting elements requiring separate adjustment, whereby much time is consumed in securing the core in place and in truing up the core.

It is the object of the present invention to provide a chuck, the radial arms of which will be advanced simultaneously by the rotation of a cam member, suitably housed in the body of the chuck, and accessible from the exterior of the body of the chuck.

A further object of the invention is to provide novel means whereby the chuck may be supported, and to provide novel means for operating the cam member, novel means being provided for holding the cam member against movement.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings,—Figure 1 is a rear elevation; Fig. 2 is a front elevation; Fig. 3 is a transverse section upon the line A—B of Fig. 2; Fig. 4 is an elevation of the cam member; and Fig. 5 is a detailed perspective of one of the arms which are advanced longitudinally, and radially of the chuck, by the cam member shown in Fig. 4.

The body of the chuck consists of a back plate 1 and a front plate 2, the latter having an outstanding peripheral flange 3, adapted to bear against the back plate, to space the back plate and the front plate slightly apart. Screws 4, or other connecting elements adapted to a like end are extended through the front plate 2, in the

flange portion 3 thereof, to engage the back plate 1, to hold the constituent elements of the body together.

The back plate 1 is supplied centrally with a hub 5, protruding beyond both faces of the back plate, the hub being provided adjacent one end with a reduced neck 6, defining a shoulder in the hub. It is against this shoulder that the front plate 2 rests, in its central portion. A supporting arm 7 of any desired form, is inserted through the hub 5 and the neck 6, the arm 7 being preferably threaded to receive a nut 8.

Disposed between the plates 1 and 2, and rotatably mounted upon the hub 5, is a cam plate 9, seen in clearest detail in Fig. 4, the cam plate being provided with a central opening 10 to receive the hub. In the cam plate 9 there are cam slots 11, each cam slot having its peculiar center of curvature, none of which centers of curvature coincide with the axis of rotation of the cam plate 9.

The back plate 1 is provided with a series of radially disposed, outstanding ribs 17, defining grooves 16 in the inner face of the back plate. In the grooves 16, arms 15 are mounted for longitudinal sliding movement, radially of the back plate 1, the arms 15 carrying at their inner ends, rollers 12, held in place upon the arms 15 by screws 14, or other securing elements, the rollers 12 being adapted to ride in the cam slots 11 of the plate 9. The arms 15 are terminally provided with enlarged heads 15, having terminal grooves 20, these grooves preferably extending circumferentially of the body of the chuck.

In the front plate 2 there is an arcuate slot 23, the center of curvature of which coincides with the axis of rotation of the cam plate 9, the construction above referred to, being most clearly discernible in Fig. 2. A plate 21, of the same curvature as the slot 23, is disposed in the slot 23, and is secured to the cam plate 9 by means of screws 22 or the like, the plate 21 being equipped with an outstanding handle 24, projecting beyond the front plate 2. Mounted in the back plate 1, adjacent the periphery thereof, and engaging the cam plate 9, is a set screw 25, or other clamping element, whereby the rotation of the cam plate may be prevented.

In practical operation, the set screw 25 is manipulated, setting the cam plate 9 free for rotation upon the hub 5. The handle 24 is then swung in the direction of the arrow

in Fig. 2, rotating the cam plate in a corresponding direction. The rollers 12 upon the arms 15 will move in the cam slots 11 of the cam plate 9 in the direction of the arrows in Fig. 4, the arms 15 sliding inwardly, in the grooves 16, toward the axis of the structure. When the arms have been retracted to the desired extent, the core is alined with the arms, whereupon the cam plate 9 is rotated in a direction opposite to that above referred to, all of the arms 15 being advanced simultaneously, away from the axis of the structure, the supporting core being engaged in the grooves 20 formed in the ends of the arms 15. Since arms 15 are advanced simultaneously, and to the same extent, the supporting core is held firmly in place, properly centered. By reason of the fact that the plate 21, carrying the handle 24, is of the same curvature as the slot 23 in the front plate 2, and by reason of the further fact that this plate 21 moves in the slot 23 in close contact with the front plate, the element 21 serves as a guide, maintaining the cam plate 9 properly positioned with respect to the other parts of the chuck, the plate 21, of course, coöperating with the hub 5 to produce this result.

Having thus described the invention, what is claimed is:

1. In a device of the class described, a body comprising a front plate having an arcuate slot; a cam member mounted for rotation in the body, the axis of rotation of the cam member coinciding with the center

of curvature of the slot; an arcuate plate secured to the cam member and moving in the slot, the said plate having a common radius of curvature with the slot and constituting a guide for the cam member; a handle carried by the arcuate plate; and radially slidable arms located in the body and engageable by the cam member for advancement and retraction. 40

2. In a device of the class described, a back plate having radial ribs defining grooves in the inner face of the back plate, the back plate being provided with a centrally disposed hub; a front plate having an outstanding flange adapted to engage the back plate to space the back plate and the front plate apart; means located in said flange for securing the plates together; a cam plate rotatably mounted upon the hub, 55 between the front plate and the back plate, the cam plate having curvilinear slots eccentric with respect to the axis of rotation of the cam plate; arms slidable in the grooves; rollers upon the arms adapted to 60 ride in the slots of the cam plate; a handle protruding through the front plate, a clamping member mounted in the back plate and adapted to engage the cam plate; and a support carried by the hub. 65

In testimony that I claim the foregoing as my own, I have hereto affixed my signature in the presence of two witnesses.

FRANKLIN WILLIAM KREMER.
